UNITED STATES PATENT OFFICE.

ALFRED CURRIER, OF GRAND RAPIDS, MICHIGAN, ASSIGNOR OF ONE-HALF
TO WILLIAM P. PUTNAM, OF SAME PLACE.

FURNITURE-CASTER.

SPECIFICATION forming part of Letters Patent No. 650,304, dated May 22, 1900.

Application filed December 11, 1899. Serial No. 739,880. (No model.)

To all whom it may concern:

Be it known that I, ALFRED CURRIER, a citizen of the United States, residing at Grand Rapids, in the county of Kent and State of Michigan, have invented certain new and useful Improvements in Furniture-Casters; and I do hereby declare the following to be a full, clear, and exact description of the invention, such as will enable others skilled in the art 10 to which it appertains to make and use the same.

My invention relates to improvements in furniture-casters, and more especially to casters adapted to be attached to an article of furniture having tubular legs; and its object is to provide the same with means whereby it may be securely attached to the leg and readily detached therefrom, as occasion may require, and also to provide means for properly 15 protecting the bolt or stud whereby the caster may be attached and to provide the device with certain new and useful features, as hereinafter more fully described, and particularly pointed out in the claims.

25 My device consists, essentially, in the combination and arrangement of a suitable bolt or stud provided with means for securing the same within the axis of the tubular leg, in combination with a cap having a recess in its under side and secured to the leg by means of the bolt and a track-plate having a suitable boss to engage the bolt and adapted to engage the rim of the cap and a caster attached to the track-plate and rotative thereon, as herein- 30 after more fully described, and particularly pointed out in the claims, reference being had to the accompanying drawings, in which—

Figure 1 is a vertical section of a device embodying my invention; Fig. 2, a horizontal 40 section of the same on the line 2 2 of Fig. 1; Fig. 3, a detail showing a plan view of the upper side of the cap; Fig. 4, a detail showing the upper side of the track-plate; Fig. 5, a detail of the under side of the track-plate; Fig. 6, the guide-ring for the rolls, and Fig. 45 7 a detail of the yoke of the caster.

Like letters refer to like parts in all of the figures.

A represents a tubular leg of a bed or other 50 article of furniture, usually made of metal pipe.

B is a suitable cap to close the lower end of the leg A and provided with an annular flange B', surrounding the lower end of the leg and having a central screw-threaded opening B" 55 to engage the stud or bolt C, arranged in the axis of the leg A, extending downward therefrom and provided with means for fixing the same within the leg, said means consisting of a series of ribs or fins D, extending in a curve 60 tangentially from the bolt C outward toward the inner surface of the tubular leg A and engaging the same, as shown in Fig. 2. The lower side of the cap B is recessed, as shown in Fig. 1, its rim extending below the end of 65 the bolt C sufficient to protect the same and prevent it from coming in contact with the floor when the caster is removed and allowing the bolt C to project within the recess of the cap sufficient to engage an upwardly-projecting 70 screw-threaded boss E' on the upper side of the track-plate E, whereby said plate is securely attached and held in contact with the under side of the cap B. The track-plate E has an annular track near its periphery traversed by the rolls G, which rolls consist of a 75 series of disks arranged in vertical planes and in openings at intervals near the rim of a ring F, said ring being freely rotative around a downwardly-projecting boss E" on the track-plate. The yoke I is provided with a corresponding track-plate H at its upper end engaging the rolls G and having a central opening K to receive the boss E", upon which boss 80 the yoke is freely rotative and to which boss 85 it is securely attached by means of an outwardly-turned flange. J is a caster-wheel journaled in the yoke I.

From the foregoing description the operation of my device will be readily understood. 90 The fins D on the bolt C extend normally outward slightly more than the radius of the interior of the tube A, and being tangential they will yield somewhat when forced into the tube, and thus securely hold the bolt C within 95 the axis of the tube A and projecting downward therefrom. The cap B is securely held in place by the bolt C and at the same time furnishes an effective protection to the projecting end of the bolt whenever the caster 100 is detached therefrom and also furnishes a suitable finish to the end of the leg formed

by the tube A. The bolt C also furnishes a secure fastening for attaching the track-plate E, which when screwed upon the bolt and turned firmly against the rim of the cap B will not readily become detached. The rolls G turn freely in the recess in the guide-ring F and furnish a suitable rolling bearing between the stationary track-plate E and the rotating track-plate H.

10 Having thus fully described my invention, what I claim, and desire to secure by Letters Patent, is—

15 1. The combination of a cap having a downwardly-projecting rim and adapted to be attached to the leg of an article of furniture, a bolt in the axis of the cap and projecting downwardly within the said rim, a fixed track-plate having an upwardly-projecting and screw-threaded boss to engage the bolt, 20 and a caster engaging the track-plate and rotating thereon, substantially as described.

2. The combination of a cap adapted to be attached to a tubular leg and having a downwardly-projecting rim, a screw-threaded bolt projecting downwardly within the rim of the cap, a track-plate having a screw-threaded,

upwardly-projecting boss to engage the bolt, and a downwardly-projecting boss to engage the yoke, a yoke having a track-plate provided with a central opening to engage the 30 boss and secured thereto, and rolls between the respective track-plates, substantially as described.

3. The combination of a cap having a downwardly-projecting rim, and a central screw-threaded bolt projecting downwardly within the rim, a track-plate having an upwardly-projecting boss screw-threaded to engage the bolt, and a downwardly-projecting boss, a 35 guide-plate having a central opening and rotative upon the boss, rolls in recesses in the guide-plate, a yoke having a track-plate having a central opening to engage the downwardly-projecting boss and secured thereto, 40 substantially as described.

45 In testimony whereof I affix my signature in presence of two witnesses.

ALFRED CURRIER.
